FIG. 3 is a front elevation view thereof;
FIG. 4 is a rear elevation view thereof;
FIG. 5 is a top plan view thereof;
FIG. 6 is a bottom plan view thereof;
FIG. 7 is a left side elevation view thereof; and
FIG. 8 is a right side elevation view thereof;

FIG. 9 is a front perspective view of a second embodiment of a male power connector housing, showing my new design;
FIG. 10 is a rear perspective view thereof;
FIG. 11 is a front elevation view thereof;
FIG. 12 is a top plan view thereof;
FIG. 13 is a left side elevation view thereof; and
FIG. 14 is a right side elevation view thereof;
FIG. 15 is a front perspective view of a third embodiment of a male power connector housing, showing my new design;
FIG. 16 is a rear perspective view thereof;
FIG. 17 is a front elevation view thereof;
FIG. 18 is a top plan view thereof;
FIG. 19 is a left side elevation view thereof; and
FIG. 20 is a right side elevation view thereof;
FIG. 21 is a front perspective view of a fourth embodiment of a male power connector housing, showing my new design;
FIG. 22 is a rear perspective view thereof;
FIG. 23 is a front elevation view thereof;
FIG. 24 is a top plan view thereof;
FIG. 25 is a left side elevation view thereof; and
FIG. 26 is a right side elevation view thereof;
FIG. 27 is a front perspective view of a fifth embodiment of a male power connector housing, showing my new design;
FIG. 28 is a rear perspective view thereof;
FIG. 29 is a front elevation view thereof;
FIG. 30 is a top plan view thereof;
FIG. 31 is a left side elevation view thereof; and
FIG. 32 is a right side elevation view thereof;
FIG. 33 is a front elevation view of a sixth embodiment of a male power connector housing, showing my new design;
FIG. 34 is a front elevation view of a seventh embodiment of a male power connector housing, showing my new design;
FIG. 35 is a front elevation view of an eighth embodiment of a male power connector housing, showing my new design;
FIG. 36 is a front elevation view of a ninth embodiment of a male power connector housing, showing my new design;
FIG. 37 is a front elevation view of a tenth embodiment of a male power connector housing, showing my new design; and,
FIG. 38 is a front elevation view of an eleventh embodiment of a male power connector housing, showing my new design.
The rear elevation view, the top plan view, the bottom plan view, the left side elevation view, and the right side elevation view of embodiments 6, 7, 8, 9, 10 and 11 are the same as that of in embodiment 1, with only difference of the location of 2 small tabs as shown in each embodiment's front elevation view.
